William H. Wellsteed, Inventor

UNITED STATES PATENT OFFICE.

WILLIAM H. WELLSTEED, OF BRAMPTON, MICHIGAN.

ANTIREFILLING BOTTLE.

SPECIFICATION forming part of Letters Patent No. 568,388, dated September 29, 1896.

Application filed October 10, 1895. Serial No. 565,277. (No model.)

To all whom it may concern:

Be it known that I, WILLIAM H. WELLSTEED, a citizen of the United States, residing at Brampton, in the county of Delta and 5 State of Michigan, have invented a new and useful Antirefilling Bottle, of which the following is a specification.

The invention relates to improvements in antirefilling bottles.

10 The object of the present invention is to improve the construction of antirefilling bottles and to provide a simple, inexpensive, and efficient one which will permit the original contents of a bottle to be readily decanted and which will effectually prevent the introduction of any liquid into it after its original filling.

15 A further object of the invention is to provide such an antirefilling bottle which will be adapted to receive the ordinary cork or stopper and which may be sealed in the usual manner.

20 The invention consists in the construction and novel combination and arrangement of 25 parts hereinafter fully described, illustrated in the accompanying drawings, and pointed out in the claims hereto appended.

25 In the drawings, Figure 1 is a vertical sectional view of an antirefilling bottle constructed in accordance with this invention. Fig. 2 is a horizontal sectional view. Fig. 3 is a detail view of the upper section of the device for preventing refilling. Fig. 4 is a similar view of the lower section of the same. Fig. 5 is a detail view of the elastic disk.

30 Like numerals of reference indicate corresponding parts in all the figures of the drawings.

35 1 designates a device adapted to be secured 40 within the neck 2 of a bottle 3 to prevent the latter from being refilled, and comprising an upper disk-shaped section 4, provided with fastening devices or bolts 5 for engaging the interior of the neck of the bottle, a lower 45 disk-shaped section 6, having a valve, and an elastic disk 7, interposed between sections 4 and 6 and coöperating with the valve to prevent refilling.

40 The upper section 4 is provided at its periphery with notches 8, forming passages to 50 permit the outward flow of the liquid contained in the bottle in decanting the same, and

also to admit air to take the place of the liquid decanted to cause the liquid to run freely from the bottle. The fastening devices or 55 bolts are preferably two in number, and are disposed diametrically opposite each other in radial perforations or openings of the upper section, and their inner ends are engaged by a spring 9, arranged within a cavity of the 60 lower face of the upper section. The cavity is substantially semispherical, and when the device is inserted in the neck of the bottle the bolts or fastening devices are compressed within their housings and are adapted to 65 spring outward into engagement with an annular curve or recess 10 of the inner face of the neck of the bottle, whereby the device is securely locked in the neck 2.

70 The lower section 6, which is connected by bolts or fastening devices 11 with the upper section, is provided in its upper face with a substantially conical opening 12, forming a valve-seat and receiving a conical valve 13, which, when the bottle is in an upright position, rests upon the seat and closes the bottle and prevents any liquid from being introduced therein. When the bottle is inverted for decanting the liquid, the valve leaves the valve-seat and the liquid is permitted to flow 75 outward. An elastic band or facing 14 is arranged in an annular groove or recess in the periphery of the lower section, and is adapted to fit against the inner face of the neck of the bottle to make a liquid-tight joint to prevent 80 the escape of any liquid at that point.

85 In order to prevent the liquid from being introduced into the bottle, when the latter is inverted, by a pump or other apparatus, the elastic disk 7 is interposed between the upper and lower sections, and is provided with a central opening of less diameter than the upper portion or base proper of the inverted conical valve 13. The pressure resulting from an attempt to refill a bottle in this manner causes the elastic disk to press against the conical valve, and the latter is thereby forced against its seat, consequently preventing any liquid from entering the bottle.

90 The neck of the bottle is provided on its 95 interior with an inwardly-projecting annular shoulder 15, which forms stops to prevent the valve mechanism from being forced into the bottle. The spring-actuated fastening

devices will lock the device in the neck of the bottle and prevent it from being drawn out; but the shoulder 15 will absolutely prevent the device from being forced into the bottle, even although the device should be subjected to pressure sufficient to injure the fastening devices 5, as the neck of the bottle is constricted at this point and will be broken if subjected to too great a pressure.

10 The parts of the device may be constructed in any suitable material which will not affect the contents of the bottle, and after the device has been placed in the neck of the bottle the latter may be corked and sealed like bottles of the ordinary construction.

15 It will be seen that the antirefilling bottle is exceedingly simple and inexpensive in construction, that it is positive and reliable in operation, and will effectually prevent a bottle from being refilled.

20 Changes in the form, proportion, and minor details of construction may be resorted to without departing from the spirit or sacrificing any of the advantages of this invention.

25 What I claim is—

1. The combination with a bottle, of a disk-shaped upper section provided with passages and arranged within the neck of the bottle, a disk-shaped lower section connected with the upper section, arranged within the neck of the bottle and provided with a valve, and an elastic disk of flexible material interposed between the two sections arranged contiguous to the flange and adapted to be forced into contact with the same by external pressure, whereby the valve will be closed when it is attempted to introduce a liquid into the neck of the bottle, substantially as described.

35 2. The combination with a bottle, of an up-

per disk-shaped section arranged within the neck of the bottle and provided with passages, a lower disk-shaped section arranged within the neck of the bottle, connected with the upper section and provided with an opening forming a valve-seat, a valve-plug arranged on the valve-seat and adapted to move outward away from the same when the bottle is inverted, and an elastic disk of flexible material interposed between the two sections, provided with an opening adjacent to the valve-plug and arranged contiguous to and adapted to engage the same, whereby the valve will be closed by external pressure, substantially as and for the purpose described.

3. In an antirefilling bottle, the combination with a neck provided with an interior groove or recess, of an upper section provided with peripheral notches or recesses forming passages, radially-disposed, spring-actuated fastening devices mounted on the upper section and engaging the curve or recess of the neck, a lower section secured to the upper section and provided at its upper face with an annular opening forming a valve-seat, a conical valve-plug arranged on the seat and adapted to move outward when the bottle is inverted, and an elastic disk interposed between the upper and lower sections and provided with a central opening and arranged to engage the top of the valve-plug, substantially as and for the purpose described.

In testimony that I claim the foregoing as my own I have hereto affixed my signature in the presence of two witnesses.

WILLIAM H. WELLSTEED.
